UNITED STATES PATENT OFFICE.

CARL HENDERSON, OF OAK PARK, ILLINOIS, ASSIGNOR TO MIEHLE PRINTING PRESS & MANUFACTURING COMPANY, OF CHICAGO, ILLINOIS, A CORPORATION OF ILLINOIS.

GRIPPER DEVICE.

1,300,610.

Specification of Letters Patent. Patented Apr. 15, 1919.

Application filed August 8, 1917. Serial No. 185,034.

To all whom it may concern:

Be it known that I, CARL HENDERSON, a citizen of the United States, residing at Oak Park, in the county of Cook and State of Illinois, have invented certain new and useful Improvements in Gripper Devices, of which the following is a specification.

The invention is an improvement upon the construction forming the subject matter of 10 my co-pending application Serial No. 85,779 filed March 22, 1916.

Heretofore it has been usual to provide gripper pads having a smooth upper face and, coöperating therewith, rigid grippers 15 having a rugose face between which rough face of the gripper finger and smooth face of the pad the sheet of paper was gripped.

A disadvantage of this construction was that if there occurred any lateral movement 20 of the gripper finger relative to the pad, the paper had a tendency to follow the movement of the gripper and slip on the pad, destroying the accuracy of its register. A further objection was that where there was 25 a variation in the thickness of the paper and not a corresponding adjustment to the throw of the gripper, the paper was mutilated and the gripped mechanism subjected to injury.

I overcome both of these objections by 30 roughening the face of the pad instead of the gripper, and by making the gripper finger yielding instead of rigid, whereby the gripped sheet retains its position on the pad notwithstanding any slippage or inaccuracy 35 of stroke of the gripper, and the gripper finger acts upon the sheet with a soft elastic pressure instead of a harsh unaccommodating grip of the former construction.

In order that the invention may be readily 40 understood, a preferred embodiment of the same is set forth in the accompanying drawings and in the description based thereon. As, however, the invention is susceptible of embodiment in other and various forms, 45 the drawing and description are to be taken in an illustrative and not necessarily limiting sense. In the drawings:

Figure 1 is a fragmentary cross-sectional view through a portion of the printing cylinder showing in side elevation the arrangement of the gripper, the gripper pad and the blanket clamping device;

Fig. 2 is a front view of the combined

blanket clamp and gripper pad support, showing the gripper pad fixed in adjusted 55 position;

Fig. 3 is a perspective view of the gripper pad; and

Fig. 4 is a side detail elevation of the gripper finger.

In the drawings the cylinder is indicated at 11 mounted in the usual way in the side frame of the press and cut away at 12 to provide for the mounting of various devices by means of which the blanket or 65 plate is clamped in position and the gripper pads are held in properly adjusted positions for coöperation with the grippers themselves.

As illustrated, upon the side wall of the 70 cut away portion 12 of the cylinder is disposed a bracket 13 serving as a support for the shaft 14, the angular position of which is controlled by means of the arm 15 and the set screw 16. Upon this shaft at proper 75 intervals are mounted the supports 17 for the blanket clamp 18 and the gripper pad 19, these supports being held in adjusted 80 positions by means of a clamping screw 20 as will be readily understood. The shaft 21 serves as a support for the gripper 85 22, mounted in the usual manner to coöperate with the gripper pad 19.

The gripper pad 19, as shown, is an angular plate of aluminum or other suitable 85 material and comprises a horizontal portion 23 having a rugose or roughened face 23^a, and a vertical portion 24 arranged at substantially right angles thereto. The upper roughened face of the horizontal portion 23 of the pad forms a contact surface between which and the lower smooth face 22^a of the gripper 22 the sheet is arranged to be gripped, while the vertical portion 24 extends parallel to and in contact with the 95 side of the gripper pad support 17 and is provided with a slot 25 for the accommodation of a set screw 26, the end of which is threaded into the head of the gripper pad support 17.

It will be readily understood that by releasing the set screw 26 the gripper pad 19 is left free to be adjusted radially of the cylinder to the proper height to adapt the same for use with different thicknesses of 105 paper, and after adjustment the tightening

of the set screw 26 will serve to retain the gripper pad in adjusted position. Heretofore the gripper finger has been rigid and exceeding nicety of adjustment of the gripper pad has been required, the operator making a number of successive tests by placing a sheet of paper of the proper thickness on top of the pad. According to my invention, this nicety of adjustment is rendered unnecessary by reason of the fact that when the gripper pads are once arranged in substantially the proper position, they may there remain for use in connection with paper of different thicknesses, by reason of the fact that the gripper finger itself, is yielding, being made of slender spring steel, and is thus enabled to accommodate itself to different thicknesses of paper. Moreover, by roughening the upper face of the gripper 20 pad and having the lower face of the gripper finger smooth, the register of the paper is in no wise likely to be destroyed by a lateral movement of the finger, the paper tending to maintain its position with refer-

ence to the pad rather than to follow the 25 movement of the gripper.

I claim:

1. The combination with a printing press cylinder, of a gripper pad having an unyielding rough face, and a gripper finger 30 having a smooth face coöperating therewith.

2. The combination with a printing press cylinder, of a gripper pad having an unyielding rough face, and a yielding gripper finger for cooperation therewith. 35

3. The combination with a printing press cylinder, of a gripper pad having an unyielding rough face, and a yielding gripper finger having a smooth face for cooperation with the rough face of the pad. 40

In witness whereof I have hereunto signed my name in the presence of two subscribing witnesses.

CARL HENDERSON.
